UNITED STATES PATENT OFFICE.

ALANSON McD. GRAY, OF ELIZABETH, NEW JERSEY.

CHILL-PLATE.

1,322,897.

Specification of Letters Patent. Patented Nov. 25, 1919.

Application filed November 23, 1918. Serial No. 263,830.

To all whom it may concern:

Be it known that I, ALANSON McD. GRAY, a citizen of the United States, residing at Elizabeth, New Jersey, have invented certain new and useful Improvements in Chill-Plates, of which the following is a clear, full, and exact description.

My invention relates to chill plates such as are used in connection with a series of molds, 10 the chill plates being set up in alternation with the molds as exemplified in my United States Patent No. 653,235, dated July 10, 1900, and more particularly in my Patent No. 1,296,652, dated March 11, 1919. The 15 invention relates particularly to certain improvements in chill plates whereby the formation of air pockets may be more effectually avoided.

It has been found in practice that air 20 pockets are liable to form in the circulating spaces or passages of the chill plates adjacent to the top thereof, resulting in more or less irregularity in the cooling effect of the plates. In order to completely overcome 25 this difficulty, I have provided a chill plate in which there is a very small air vent formed between the baffle plates connected with the vertical wall of the chill plate, and an important feature of my invention relates to the manner of forming these minute 30 air vents.

Referring to the drawings,

Figure 1 is a longitudinal section of the chill plate;

Fig. 2 is a cross-section thereof along the line A—A, Fig. 1; and

Fig. 3 is a section on the line B—B, Fig. 1.

The chill plate may be substantially of 40 the construction shown and described in my Patent No. 1,296,652 above referred to, said construction being as follows:

The plate is narrow in cross-section and rectangular in longitudinal section, as 45 shown, to correspond to the molds with which it is used. Said plate is composed of side walls 2 having lugs or ears 4, by which it is supported in working position. Extending from the top wall 6 are baffle plates 50 8 and 10 which reach to a distance short of the bottom wall 12, and extending from said bottom wall 12 about midway between baffle plates 8 and 10, is a baffle plate 14 extending to a distance short of the top wall 6.

These chill plates with their supporting ears 55 4 are preferably made integral as castings. The cooling fluid which is circulated through each of the chill plates is supplied by an inlet pipe 16 passing through the bottom wall 12 of the plate, the circulation of the fluid 60 being downward from the inlet pipe 16 under the first baffle-plate 8, up and over the second baffle plate 14 and down and under the third baffle plate 10 and upwardly to the orifice of a discharge pipe 18, which also 65 passes through the bottom plate 12. Water is preferably used as a cooling fluid, although of course other liquids may be used as conditions may require. It has been found that the air entrained in the water 70 tends to collect in the corners formed between the baffle-plates 8 and 10 and the top wall 6 of the chill plate.

Attempts have been made to relieve this condition by drilling holes in the baffle 75 plates 8 and 10, said holes being made by a drill which necessarily passes through the side walls 2, across the space between said side wall and baffle plate 8, which space in the particular chill plate shown, is somewhat 80 over five inches. This operation necessitated the use of a drill of sufficient size to stand the strain of drilling without breaking and the hole made by it was necessarily so large that it could be easily clogged up by debris of 85 various kinds often found in the circulating water, and even by small fish, which experience has shown are often present in the water, especially where the water is taken directly from rivers or small streams. 90

In order to avoid the difficulties arising from drilling through the side walls and baffle plates and to otherwise improve the construction of chill-plates, I form holes 20 in the top plate 6 in alignment with the baffle 95 plates 8 and 10 respectively, said holes being of a depth slightly greater than the thickness of the top plate 6. After these holes are formed, they are properly tapped and a 100 plug 22 inserted which is screwed down a distance such as to leave a very minute air opening at the top of each baffle plate 8 and 10 so as to allow for the escape of air between the chambers formed on either side of the baffle plate, thus permitting the air to spread 105 out across the top of the plate and be forced down the outlet pipe 18 along with the discharging water. Preferably the holes 20 are

cast with the chill plate, which plate also has the usual core holes 24 to enable the core to be removed after the plate has been cast.

It will be seen from the construction described that if there is at any time a stoppage in the air vent, the plug may be removed and the stoppage relieved.

Having thus described my invention, what I claim and desire to secure by Letters Patent is:

1. A chill plate comprising a hollow receptacle, vertical baffle plates extending from the top wall of said receptacle to a distance short of the opposite wall, said baffle plates directing the course of circulation of the cooling fluid through said receptacle, and inlet and outlet openings for the cooling fluid, at least one of said baffle plates having a minute air vent therethrough between the baffle plate and the top wall of said receptacle to prevent air pockets being formed in the top of the receptacle.

2. A chill plate comprising a hollow receptacle, vertical baffle plates extending from the top wall of said receptacle to a distance short of the opposite wall, said baffle plates directing the course of circulation of the cooling fluid through said receptacle, inlet and outlet openings for the cooling fluid and a minute air vent leading from one side to the other of at least one of said baffle plates between the baffle plate and the top wall of said receptacle to prevent air pockets being formed in the top of the receptacle.

3. A chill plate comprising a hollow receptacle, vertical baffle plates extending from the top wall of said receptacle to a distance short of the opposite wall, said baffle plates directing the course of circulation of the cooling fluid through said receptacle, inlet and outlet openings for the cooling fluid, the top wall of said receptacle having a hole formed therein in alinement with each of

said baffle plates, said hole extending to a distance slightly greater than the thickness of said top wall and a plug inside said hole of a length such as to leave a very small air-vent across the baffle plate to prevent air pockets being formed in the top of the receptacle.

4. A chill plate formed of cast metal and comprising a hollow receptacle having vertical baffle plates extending from the top wall thereof to a distance short of the opposite wall thereof, said top wall having a hole cast therein in alinement with each of said baffle plates, such hole extending a distance slightly greater than the thickness of the top wall.

5. A chill plate comprising a hollow receptacle, vertical baffle plates extending from the top wall of said receptacle to a distance short of the opposite wall, said baffle plates directing the course of circulation of the cooling fluid through said receptacle, and inlet and outlet openings for the cooling fluid, a plurality of said baffle plates having a minute air vent therethrough between each baffle plate and the top wall of said receptacle to prevent air pockets being formed in the top of the receptacle.

6. A chill plate comprising a hollow receptacle, vertical baffle plates extending from the top wall of said receptacle to a distance short of the opposite wall, said baffle plates directing the course of circulation of the cooling fluid through said receptacle, inlet and outlet openings for the cooling fluid, and a minute air vent leading from one side to the other of a plurality of said baffle plates between each baffle plate and the top wall of said receptacle to prevent air pockets being formed in the top of the receptacle.

Signed at New York, N. Y., this 6th day of November, 1918.

ALANSON McD. GRAY.
